US00D567685S

(12) **United States Design Patent** (10) Patent No.: **US D567,685 S**
(45) Date of Patent: **** Apr. 29, 2008**

(54) **LINE LASER DEVICE**

(75) Inventor: **Marco Burkhardt**, Isernhagen (DE)

(73) Assignee: **Leica Geosystems, AG**, Heerbrugg (CH)

(**) Term: **14 Years**

(21) Appl. No.: **29/277,304**

(22) Filed: **Feb. 21, 2007**

(51) **LOC (8) Cl. 10-04**

(52) **U.S. Cl. D10/69**

(58) **Field of Classification Search** D10/69, D10/70; 33/276, 277, 281, 285, 286, 290, 33/291-299, DIG. 21; 340/573.1, 573.4, 340/539, 825.36, 825.46, 825.49, 555-557; 356/5.15, 4.01, 5.01, 4.05, 5.05-5.09, 5.12, 356/28.5, 345, 375, 3, 128-155, 399-400; 385/83, 97-99, 134-139; 701/211-213, 701/150, 158; 264/1.24-1.25

See application file for complete search history.

(57) **CLAIM**

The ornamental design for a line laser device, as shown and described.

DESCRIPTION

FIG. 1 is a left side elevational view of the device of FIG. 4;

FIG. 2 is a rear view;

FIG. 3 is a right side elevational view;

FIG. 4 is a front elevational view showing my new design;

FIG. 5 is a top plan view;

FIG. 6 is a bottom plan view; and,

FIG. 7 is a front perspective view.
